UNITED STATES PATENT OFFICE.

JOSEPH L. DE GOOD, OF DETROIT, MICHIGAN, ASSIGNOR TO HENDERSON N. WHITE, OF CLEVELAND, OHIO.

TROMBONE.

971,833.

Specification of Letters Patent.

Patented Oct. 4, 1910.

Application filed January 4, 1907. Serial No. 350,715.

To all whom it may concern:

Be it known that I, JOSEPH L. DE GOOD, a citizen of the United States, residing at Detroit, county of Wayne, State of Michigan, have invented a certain new and useful Improvement in Trombones, and declare the following to be a full, clear, and exact description of the same, such as will enable others skilled in the art to which it pertains 10 to make and use the same, reference being had to the accompanying drawings, which form a part of this specification.

This invention relates to trombones; it has for its object improved connections between that part of the extensible tube, which is fixed to the bell of the trombone and the removable or sliding part thereof.

In the drawings:—Figure 1, shows a trombone in elevation, a part of the sliding tube, and a part of the slide on the fixed member, being broken away. Fig. 2, is a longitudinal section through my improved connection. In this figure the broken-off portion to the right of the main portion of 20 the figure would, if the entire tubular connection were shown, be considerably extended to the right of its present ending. Fig. 3, is a perspective, showing an additional bearing sleeve member. Fig. 4, is a 25 longitudinal section through that portion of both of the tubes constituting the outer or inclosing slide member, and extending a short distance on each side of each, the section showing a portion of the tubing on each 30 side of the crosswise hand-bar by pressure upon which the movable sound-regulating tubes are adjusted, with respect to the mouth and bell portion, to produce the variety of tones desired.

40 1 indicates the bell of the trombone, and 2 the mouth piece.

3 indicates a tube extending from the bell to the point of connection of this part with the sliding member.

45 4 indicates a curved sliding tube, which connects the tube 3 with the mouth piece 2 through the intervening members herein-after to be described, being adjustable in order to vary the tone of the instrument.

50 50 The mouth piece 2 is inserted in a sleeve 5, from which extends a long tube 6, which engages within the members 7 of the curved sliding tube 4. A sleeve 8, similar to the sleeve 5, forms a coupling between the tube 55 3 and the tube 9, which projects parallel

with, and is of equal length with, the tube 6. Between that end of the tube 6 which is nearest the mouth piece 2, and the sleeve 5, is an annular chamber within which one end of a bearing sleeve 10 engages. This and its 60 companion sleeve 11, which occupies the same relation to the inner tube 9, are firmly, though removably, fixed within the adjacent ends of the tubes 7 and 7^a, respectively, and, with them, are capable of slidable 65 movement along, and with respect to, the inner tubes 6 and 9. These tubes 6 and 9 are provided with enlarged end portions 12—12^a, of which one is seen in Fig. 2, of such diameter as to fit closely, though slidably, inside of the member 7^a, their object 70 being to make a tight-fitting joint between it and the inner end of the tubes 6 and 9.

The bearing sleeve 10 is a tubular member provided with a collar 13, about midway of 75 its length; that portion between the collar and the end which is toward the tube 7 is of such diameter as to fit tightly within it when forced thereinto. The corresponding part of the bearing sleeve 11, between the 80 collar 14 and the end, engages within the member 7^a. That portion of the bearing sleeve 10 which is between the collar 13 and the sleeve 5, engages loosely in the end portion thereof, and that portion of the sleeve 85 11 between the collar 14 and the sleeve 8 similarly engages in the annular chamber at the end of the sleeve 8. The cross-piece 15, Fig. 1, is the usual brace between coupling 90 parts 5 and 8, and cross-piece 16 is the usual brace between end sleeves 17—17^a on tubes 7 and 7^a respectively.

With this construction, the sliding tube can be moved in the ordinary way, and in this movement the bearing sleeves 10 and 11, 95 travel with the sliding members 7 and 7^a, to which they are held by their tight engagement; in this travel, they slide easily and smoothly on the tubes 6 and 9. The movement of the one part upon the other is on 100 bearing parts at the free ends of the outer tubes 7 and 7^a, and this causes a smooth movement in place of the inaccurate rocking movement which takes place when the space between the outer and inner tubes is not 105 filled, as is necessary when that space is sufficiently large to allow the introduction of the inner tubes with enlarged piston-like ends, that have heretofore been used. When the tubes 7 and 7^a are drawn out, with respect to 110

the tubes 6 and 9, these bearing sleeves co-
operate with these enlarged end portions in
furnishing suitably spaced bearing surfaces,
each fitting tightly within one of the tubes
5 7 or 7^a, for the sliding of the tubes 6 or 9.
When the sliding tube portion 4 is moved as
far toward the mouth piece portion of the
trombone as possible, of course the enlarged
piston ends of the tubes 6 and 9, and the
10 bearing sleeve portions 10 and 11, are as far
away from one another as is possible.
When, however, the curved sliding portion 4
is moved outwardly to produce various notes,
the bearing points constituted for each of
15 the tubes 7 and 7^a by the enlarged piston
ends of the tubes 6 and 9, and the bearing
sleeves 10 and 11, approach one another, so
that when the sliding tube portion 4 is at the
outer limit of its travel, the enlarged por-
20 tions 12 abut against the outer ends of the
bearing sleeve portions. In this position,
the space between the bearing points is not
merely the distance from the enlarged piston
portions 12 to the then quite inner ends
25 of the tubes 7 and 7^a, but in addition, the
distance from the collars 13 and 14 on these
bearing sleeves 10 and 11 (which are then
abutting closely against the ends of the tubes
7 and 7^a) to the opposite end of these bear-
30 ing sleeve members, that is, the end toward
the mouth piece 2, since this part of each
bearing sleeve at all times projects beyond
the end of its tube 7 or 7^a. The wearing
of the walls of the tubes by the rocking of
35 one tube 7 or 7^a, with respect to its telescoping
tubes 6 or 9, is thus prevented, and the
short bearing surface of the enlarged piston
ends of the tubes 6 and 9, which this ar-
rangement makes possible—merely enough
40 to render its engagement within its inclosing
tube 7 or 7^a air tight—reduces to a desirable
degree the frictional resistance to the move-
ment of the entire sliding tube 4, as the in-
strument is played.
45 Preferably the outer end of the sleeve 8,
into which the adjacent end of the bearing
sleeve 11 is adapted to engage when the
curved sliding tube 4 is moved as far toward
the mouth piece portion 2 as possible, is pro-
50 vided with a cushioning packing 16, against
which the end of the bearing sleeve 11 seats
when the parts are in this position; and so
also the length of the outer tube 7^a and the
inner tube part 9, is preferably so propor-
55 tioned that the expanded piston end 12 does
not strike or engage against the end of the
bearing sleeve 11 within the tube 7^a, even

when the trombone has been moved to the so-called "seventh position".

It is obvious that the sliding tube may, at 60
any time, be entirely removed from the in-
ner members, if this be desired for any pur-
pose.

What I claim is:—

1. In a trombone, in combination with a 65
bell portion and a mouth piece portion in
fixed relation to one another, a pair of inner
tube members fixed with respect to said bell
and mouth piece portions, enlarged termi-
nals at the end of each, complementary outer
70 tubes joined at their outer ends adapted to
slidably engage thereover, and, with whose
inner faces said enlarged terminals closely en-
gage, and a removable bearing sleeve fitting
closely for a portion of its length only within
75 the end of each outer tube and fitting
closely about the corresponding inner tube,
adapted to coöperate with the enlarged piston
terminal portion in constituting elongated
bearing for the relative movement of 80
the inner and outer tubes.

2. In a trombone, in combination with a
bell portion and an adjacent tubular portion
occupying a fixed relation with respect thereto,
a pair of inner tube members projecting 85
from said tubular portion in parallel rela-
tion, a pair of outer tubes adapted to engage
slidably over said inner tube members, en-
larged terminal portions carried by said in-
ner tubes and adapted to fit closely within
90 said outer tubes, bearing sleeve members re-
movably fixed within the inner end of said
outer tubes, each having a portion of its
length projecting outside of its tube toward
the fixed portions of the trombone, and co-
95 operating with said enlarged terminal por-
tions by engagement about said inner tubes
in furnishing a plurality of longitudinally
spaced bearing surfaces for the relative
movement of the inner and outer tubes. 100

3. A slide trombone, comprising an outer
tubular member having two ends and a de-
tachable bearing at each end, and an inner
tubular member having two ends and slid-
ably mounted in said bearings and having 105
bearings at its ends in said outer member,
said several bearings taking the wear be-
tween said members.

In testimony whereof, I, sign this specifica-
tion in the presence of two witnesses.

JOSEPH L. DE GOOD.
